(57) **CLAIM**

The ornamental design for a razor cartridge as shown and described.

DESCRIPTION

FIG. 1 is perspective view of a first embodiment of a razor cartridge;

FIG. 2 is a front view thereof;

FIG. 3 is a back view thereof;

FIG. 4 is a left side view thereof;

FIG. 5 is a right side view thereof;

FIG. 6 is a top view thereof; and

FIG. 7 is a bottom view thereof.

FIG. 8 is perspective view of a second embodiment of a razor cartridge;

FIG. 9 is a front view thereof;

FIG. 10 is a top view thereof;

FIG. 11 is a bottom view thereof; and

FIG. 12 is perspective view of a third embodiment of a razor cartridge;

FIG. 13 is a front view thereof;

FIG. 14 is a top view thereof;

FIG. 15 is a bottom view thereof; and

FIG. 16 is perspective view of a fourth embodiment of a razor cartridge;

FIG. 17 is a front view thereof;

FIG. 18 is a top view thereof;

FIG. 19 is a bottom view thereof; and

FIG. 20 is perspective view of a fifth embodiment of a razor cartridge;

FIG. 21 is a front view thereof;

FIG. 22 is a top view thereof;

FIG. 23 is a bottom view thereof; and

FIG. 24 is perspective view of a sixth embodiment of a razor cartridge;

(Continued)

FIG. 25 is a front view thereof;
FIG. 26 is a top view thereof; and,
FIG. 27 is a bottom view thereof.

The back view, left side view and right side view of Embodiments 2-6 are the same as the back view, left side view and right side view of Embodiment 1. The broken lines in the drawings illustrate portions of the razor cartridge that form no part of the claimed design. In the drawings, the stippled shadings of different density illustrate contrast in appearance.
